UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

RAILWAY CAR.

Application filed August 29, 1924. Serial No. 734,841.

My invention relates to improvements in railway cars.

An object of the invention is to improve the construction of car sides whereby the same may be formed of sufficient strength to transmit a large proportion of the load to the bolsters and to so form the side wall that the bottom chord will be out of contact with the lading in the car and thereby not subjected to corrosion. Heretofore it has been the practice to extend the side wall of a gondola type of car to a considerable distance below the floor thereof and attach near the lower margin thereof the lower chord, but such a construction is heavy and expensive and when used in connection with drop doors in the floor of the car, the drop doors and operating mechanism thereof are obscured from view and the operator is hampered in the manipulation of the door mechanism.

It is also an object of the invention to form the lower margin of the car sides of restricted width while still maintaining the same of sufficient strength to resist buckling of the side wall.

A more specific object of the invention is to provide a convenient means of attaching the side walls to the transverse beams of the car.

Further, my invention resides in certain novelties of construction and arrangement of parts such as will be more particularly pointed out in this specification and claims.

In the drawings forming a part of this specification, Figure 1 is a side elevational view of the end portion of a gondola type of car showing my improvements in connection therewith, the portion shown representing slightly less than one-half thereof. Figure 2 is a plan view of the car taken on a section line corresponding substantially to a line 2-2 of Figure 1, the section showing slightly more than half the width of the car. Figure 3 is a transverse, sectional view of a portion of the car and is taken on a line corresponding substantially to the line 3-3 of Figure 2. Figure 4 is a view of a portion of the side of the car illustrating on an enlarged scale the side door locking and raising mechanism in relation to the side of the car. Figure 5 is a transverse, sectional view of Figure 4 as viewed on the line 5-5. Figure 6 is a vertical, transverse, sectional view taken through the side of the car and on a line corresponding substantially to a line 6-6 of Figure 1.

In said drawings the car is shown as of the gondola type, such car including side wall A, end wall B, floor C, center sills D, floor door E, and door operating mechanism F. It will, of course, be understood that the construction of the car will be duplicated on each side of the center sill and that the two ends of the car are similar but description will be confined only to such portion of the car as shown.

The side wall A of the car is of the plate girder type, including side plate 10, top member 11, bottom member 12 and side stakes 13. The end wall B of the car includes a plate 14, top member 15 and suitable reinforcements 16 extending transversely of the car. Connection between the end wall and each side wall of the car is made by forming the plate 14 with a flange 17 at the corresponding side edge and disposing an angle 18 within the car. The end wall B of the car is extended downwardly beyond the side wall A of the car and a connecting gusset plate 19 serves to connect said downwardly extending portion of the end wall B with the side wall A by means of rivets 20 which pass through the bottom member 12 of the car, it being understood that this latter member is preferably extended from end to end of the car. This form of connection serves to brace the car against racking and forms a very effective support for the push pole pocket 21 which is mounted on the corner of the car. Said bottom member 12 is of angular shape and preferably consists of a bulb angle member disposed as shown with one flange 22 resting on the body bolster 23 and the other flange 24 of the angle depending downwardly with the bulb portion 25 thereof defining the lower margin of the car side. A series of transverse cross-beams 26 extend outwardly from the center sills, said cross-beams including diaphragms of pan shaped formation with a horizontally extending top flange 27 and vertically extending end flange 28 and to these each bulb member is secured as shown at 27a and 28a, respectively. To accommodate the bulb portion of the angle the outer flanges of the transverse members are cut out as indicated at 29, the stakes 13 being extended downwardly beyond the bulb angle. Suitable con-

nections are made between each stake 13 and cross-beam 26, both directly by means of rivets 30 and also through the medium of the connection angle 31. The car floor C is flanged upwardly as indicated at 32 and thereby secured to the side wall of the car by means of rivets 33 and is also secured to the horizontal flange 22 of the bulb angle member 12. The disposition of the car floor in this manner serves the two-fold purpose of a protection for the main load resisting member 12, guarding the same against corrosion and also constitutes a valuable strengthening member working in unison with the member 12 to maintain the car square and true.

The floor door E is of the usual type, hinged at the center sill as at 34, while the winding and lifting mechanism 35 is of the type shown and fully described in my pending application, Serial No. 691,830, filed February 9, 1924. Said mechanism 35 is carried by a lifting shaft 36 rotatably mounted in bearings 37 secured to the outer ends of the crossbeams. The end bearing member 37 is extended downwardly and has a flange 38 secured to the lower portion of the adjacent side stake 13 by means of rivets 39. Said member 37 is also provided with a horizontal flange 40 which extends below the horizontal flange of the crossbeam 26 and is secured thereto by means of rivets 41. Said member 37 carries a locking pawl 42 adapted to co-operate with a ratchet wheel 43 rigidly secured to the shaft 36 and whereby the shaft is locked against reverse rotation. A locking cam 44 is also pivotally mounted on the bracket 37 and is adapted to co-operate with the lower portion of the pawl 42 to maintain the same in locked position with respect to the ratchet wheel 43. Rotation of the shaft 36 is effected by means of an oscillatable lever 45 pivotally mounted near the end thereof. Said lever is loosely mounted on the shaft but co-operation between the lever and shaft is assured through the medium of pawls 46 engaging with a ratchet wheel 47, one of said pawls being adapted to effect rotation of the shaft in one direction and the other of said pawls being adapted to effect rotation of the shaft in the opposite direction.

The connection of the bracket 37 to both the stake 13 and the crossbeam 26 in the manner indicated forms an exceptionally strong connection and one which thoroughly guards against overturning of the bracket 37 due to the load imparted thereon by the pawl 42 as the latter serves to restrain the doors from opening and also forms a secure heel for the stake 13.

It will be seen that the construction of the lower portion of the side provides a lower chord of great strength, which is protected from corrosion and also permits of strong

attachment to the transverse members of the underframe. Furthermore, the operating shaft being located below the bulb member 12 it is not obscured from view of the operator and the parts of the door operating mechanism are visible and very accessible to the operator. As will be noted by inspection of Figure 5, the lever 45 can be swung through a relatively large arc as indicated by the conventional curved line designated by 48.

While I have shown my improved construction applied in connection with a car having dump doors arranged to swing on axes arranged longitudinally of the car, I do not wish to limit my improvements to a car of this type, but it will be understood that the same is applicable to various types of cars, for instance the doors might be arranged to swing on axes extending transversely of the car, and I contemplate all constructions which come within the scope and spirit of the following claims.

What I claim is:

1. In a railway car, the combination with an underframe including a transverse beam member; of a side wall having a stake secured thereto and extending below the transverse beam; a dump door in the floor of the car; means for operating the door; ratchet means cooperating with said operating means; a pawl co-acting with the ratchet means for preventing retrograde movement of said operating means; and a flanged bracket on which said pawl is pivotally mounted, said bracket being secured by its flanges respectively to the transverse beam and to the downwardly extending portion of the side stake.

2. In a railway car, the combination with an underframe including a transverse beam member; of a side wall having a stake secured thereto and extending below the transverse beam; a dump door in the floor of the car; a door operating shaft; and a bracket having a bearing for said shaft, said bracket being secured to that portion of the stake which extends below the transverse beam.

3. In a railway car, the combination with the transverse beams of the underframe; of an end sheet; a side sheet having the lower portion thereof depending below the floor of the car; an angular member secured to such depending portion of the side sheet and having one flange secured to the transverse beams and having the other flange depending below the same and secured to the side sheet; and a gusset connection between the angular member and the end sheet.

4. In a railway car side, a lower chord formed of two angularly shaped metallic members, one of which forms a floor portion of the car, said members extending longitudinally substantially the full length of the car side and having horizontally ar-

ranged inwardly disposed flange portions placed back to back and secured together, one of said members having its vertically disposed flange extending upwardly from the horizontal flange and the other of said members having a flange extending below the said horizontal flange, said upwardly and downwardly extending flanges lying in a common substantially vertical plane, the 10 downwardly extending vertical flange on its lower extremity being provided with a bulb formation; and metallic side wall sheeting overlapping said vertically extending flanges and being rigidly secured to both of them.

15 5. In a railway car side, a lower chord formed of two angularly shaped metallic members extending longitudinally the full length of the car side and having horizon-

tally arranged inwardly disposed flanges secured together, one of said members having 20 its vertically disposed flange extending upwardly from said horizontal flange, and the other of said members having a flange extending below the horizontal flange thereof, said flanges lying in a common substantially 25 vertical plane, and the lower flange on its lower extremity being provided with a bulb formation; and metallic side wall sheeting overlapping both of said vertically extending flanges and being secured to the vertical 30 flanges of both of said angularly shaped members.

In witness that I claim the foregoing I have hereunto subscribed my name this 18th day of August, 1924.

ARGYLE CAMPBELL.
